AUTOMATIC BOOK CUTTING-OFF DEVICE

Winifred A. Larkins, Kingsport, Tenn.

Application June 21, 1948, Serial No. 34,318

1 Claim. (Cl. 112—252)

1

This invention relates to machines for stitching together the folded edges of book signatures that are successively fed to the stitching means but more particularly and specifically it is directed to the means with which the machine is provided for severing the stitching threads between the last signature of one book and the first signature of the following book.

The purpose of this invention is to improve book signature stitching machines by reciprocating the cutting knives instead of the pressure plates.

Primarily this invention has as an object the provision of new and useful improvements in the stitching thread severing means of a book stitching machine. In such popular book stitching machines the means for severing the stitching threads between the signatures of books have consisted primarily of presser plates that level the backs of the signatures as they are fed to the stitching position and which resist the upward thrust of the punches which pierce the holes for the needles and to guide the hooks and needles as they descend and pass through the pierced holes in the edges of the signatures.

The main object of the present invention is to simplify and to make more efficient and durable the thread cutting means of such book stitching machines which is accomplished in the present instance by a new and novel construction of the presser plates and of the thread cutting knives which operate in conjunction therewith.

Another important object of this invention resides in the provision of such thread severing means as have been set forth which are relatively inexpensive of design and manufacture and which may be easily installed to replace those cutting means now employed on such machines. Because the presser plates and the hook plates on the present machines are quite expensive, and because the present construction of these parts permits them to be easily broken necessitating their replacement, this invention is highly desired and needed in the art.

Still further improvements and advantages of this invention will readily appear to those skilled in the art when the following description is read in the light of the accompanying drawings.

In the drawings:

Fig. 1 is a front elevation of a conventional stitching machine showing one relative position of the operable parts thereof.

Fig. 2 is a vertical section of the feeding saddle and a needle, looper, and punch being shown in their relative positions thereto.

2

Fig. 3 is a view looking upwardly toward the under surface of the cross bar of the machine showing an adjacent pair of the presser plates.

Fig. 4 is a plan view of the unit shown in Fig. 3.

Fig. 5 is a vertical section taken on line 5—5 of Fig. 3 with the machine cross bar omitted.

Fig. 6 is an enlarged transverse section through a presser plate showing certain constructional details thereof.

Fig. 7 is a view similar to Fig. 6 with the parts being shown in still another relationship.

Fig. 8 is a perspective view showing in part a pair of book pads with the signature threads cut at their junction.

Referring now to the drawing wherein like reference characters denote corresponding parts the book signature cutting off device of this invention includes a plurality of pressure or throat plates. The needles 1 and looper hooks 2 are mounted in a conventional manner whereby they may be reciprocated through a plurality of pressure plates, generally referred to by the numeral 3. Each pressure plate carries two needle guide plates 10 and two hook needle guide plates 11, and the pressure or throat plates are provided with slots 13 for the needles 1 to reciprocate in.

The conventional V-shape saddles 6 with loopers 4 therein are mounted below the pressure plates and positioned to receive the straight and looper needles, and as the signatures are formed thereon the signatures are actuated laterally under the pressure plates to an assembled position as illustrated in Figure 8.

The pressure plates are formed with sections as indicated by the letter A the thickness of which is greater than that of the plates and the plates are secured to the cross bar B of the machine by screws 12, which extend through these sections.

The number of throat or pressure plates used in these machines depends upon the sizes of the books to be stitched and the distance apart the lines of stitching are to be spaced. A single throat plate is illustrated herein as embodying the present invention and that shown is comprised of the body 3 which is designed to be secured to a supporting bar B, and members or knives 21 that are movably located in grooves 23 in the under side of the body 3. The fixed member 3 is preferably fastened in a mortise in the under face of the supporting bar by screw 12 and the grooves are of such width that the members 21 may be shifted transversely. The fixed member or pressure plate has openings 13 for the passage of the needle 1 and perforations 15 for

the passage of the looper hooks 2, and the movable member has openings 20 for the passage of the needles. The inner edges of the openings 20 in the movable members are ground down to form knife edges.

The movable members of the throat plate are fastened to a shifting bar 22 by screws 5. The bar 22 is movable lengthwise in a groove 7 in the under side of the supporting bar and is retained in the groove by the heads 8 of screws that extend through slots 9. Any suitable connection may be made between the shifting bar and operating mechanism of the machine for reciprocating the bar and shifting the movable members with relation to the fixed members at the desired times. As an illustration the sliding bar 22 is connected at the point 32 to a lever 31 that is actuated by a cam 30.

The needles and the hooks reciprocate as usual always in the same paths. As the signatures are being stitched the needles 1 which form the straight-line or tail stitches pass through needle openings 14 in the slot 13 in the fixed members of the throat plates and also through one of the openings between the knives of the movable plates, while the hooks 2 which form the chain or head stitches pass through hook perforations 15 in the fixed members only. On the start the movable members or knives are in such position that the needles draw the threads through the openings 17 in the movable members. After the last signature of a book is stitched the connecting bar is moved so as to shift the movable members sidewise and then while the needles pass through the same opening in the fixed member they pass through the openings 13 in the movable members. This causes loops of the thread to be wound around the sections 19 that are between the openings through the movable members, as shown at the top of Fig. 3. After the last signature of each book is stitched the movable members are shifted so as to loop the tail stitch threads, that is, the movable members are moved to one side and then back to the other side.

As the needles 1 form the tail stitches through the openings 17 and 18, the looper 2 carries the looper thread 53 through the opening 15 and the sliding movement of the looper hook or knife 25 causes the thread to wrap around the knife 25, as shown in Figure 3, at the same time the thread of the tail stitch is wrapped around the section 19, whereas, in the return movement in which the tail stitch is formed the thread of the double loop is looped to form the looper stitch. The knife 25 is provided with projections 26 on the sides of the end to retain the thread thereon. The stitching continues and after several signatures have been stitched the backward movement of the stitched signatures causes the threaded loops to be drawn across the knife edges of the openings through the movable members and be severed. At the same time the looper thread is drawn across the knife edge on the inner edge of the looper knife 25 whereby the looper thread is also cut. This is effected at such times that the threads are cut between the last signature of one book and the first signature of the following book, but not until several following signatures have been stitched, so that the drawing of the threads does not loosen the stitching, in fact, it tightens the stitching.

By the combination of the looper thread knife or hook 25 the chain or head stitch is formed and cut simultaneously with the tail stitch. The

L-shape knives or movable members also provide sections 27 that ride on the end surfaces of the sections A of the throat or pressure plates.

When a book is separated the ends 54, Fig. 8, 5 of the cut tail stitch threads are drawn from the tail stitching through the loops of the chain stitching on the finished book, and then through the loops of the chain stitching on the first signature of the following book. After one book 10 is stitched and before the threads are cut several signatures of the following book have been stitched so that in drawing out the threads the long ends of the threads remain in the loops of the chain and the books can be separated without loosening the stitching.

With the parts arranged in this manner the signatures are placed on the saddle 6 below the pressure or throat plates and the single thread needles 1 which form the tail stitches are reciprocated through the needle openings 14 in the plates to form a single thread, as indicated by the numeral 51, in holes that have been previously formed in the signature by punches 5, and at the same time the hook needles 2 are similarly reciprocated to form the loop or double threads, as indicated by the numerals 53 through similar holes in the signature.

What is claimed is:

In a signature stitching machine, the combination which comprises a pressure plate for use on a book signature stitching machine, said pressure plate having a slot with an enlarged needle opening in each end and also at a point midway between the ends, and also having a looper hook opening therein aligned with the needle openings of said slot, an L-shaped movable member having openings with knife edges positioned to register with the enlarged needle openings of the slot slidably mounted on the under surface 30 of the pressure plate, said movable member also having a looper knife at the end of the section thereof in which the openings positioned to register with the needle openings of the slot are positioned, a horizontally movable carrier secured 35 to said L-shaped movable member, said carrier positioned to be actuated by the stitching machine whereby the movable member moves at intervals transversely across the needle path in a plane parallel with the line between the needle 40 opening and hook opening and dwells on one side of the needle path when the signatures of one book are being stitched and then moves over and dwells on the other side of the needle path when the following book signatures are being 45 stitched, whereby at the finish of the stitching of the signatures of each book the needle and looper threads will be looped over said section and looper knife and after the feed of several following signatures will be drawn around said 50 section and looper knife to tighten the stitches and be severed.
